UNITED STATES PATENT OFFICE.

FREDERICK G. SARGENT, OF GRANITEVILLE, MASSACHUSETTS, ASSIGNOR TO C. G. SARGENT'S SONS CORPORATION, OF GRANITEVILLE, MASSACHUSETTS, A CORPORATION OF MASSACHUSETTS.

DRYING-MACHINE.

No. 874,901.

Specification of Letters Patent.

Patented Dec. 24, 1907.

Application filed September 20, 1906. Serial No. 335,348.

To all whom it may concern:

Be it known that I, FREDERICK G. SARGENT, a citizen of the United States, residing at Graniteville, in the county of Middlesex, 5 State of Massachusetts, have invented a certain new and useful Improvement in Drying-Machines, of which the following is a specification, reference being had therein to the accompanying drawings.

10 The invention relates to drying machines for handling wool and other loose material, and consists in a drier having two or more aprons, each of which carries stock through the machine, so that the stock can be fed into 15 the machine in two or more places. Also, in novel means for opening up the stock in being carried by an apron through a drier. Also, in novel means of withdrawing the moisture-laden air from the interior of the 20 machine.

The invention is illustrated in the drawings, in which latter,—Figure 1 shows in side elevation a drier containing the invention. Fig. 2 is a plan of the said drier. Fig. 3 25 shows the same in longitudinal vertical section. Fig. 4 is a partial plan with the casing of the steam-coils, *i. e.*, coil-box, partly broken away. Fig. 5 is a view in transverse section passing through the coil-box. Fig. 6 30 is a sectional detail view showing, more particularly, one of the arrangements for opening up the stock.

Having reference to the drawings,—At *a* is shown the casing of the drying-chamber, at 35 *B* the outlet duct for damp air, and at *C* is a damper in the said duct for regulating the amount of damp air that is let out.

At *D* is the casing of the steam-coils, otherwise termed coil-box, at *E*, *E*, are the steam- 40 coils, at *F* is the fan for causing the circulation of air within the drier, at *F'* the fan-shaft, and at *G* the pulley on said fan-shaft for the reception of a suitable driving-band.

At 1 and 2, respectively, are upper and 45 lower carrier-aprons, the apron 1 being supported at the opposite ends of the drying-chamber by rolls 1^a, 1^b, respectively, which are journaled in bearings supported at the exterior of the end walls of the drying-chamber, the said apron passing around the said rolls. Apron 1 is advanced, so as to carry 50 the stock which is supported thereby through the drying-chamber, by means of a driving-

band 1^c passing around a band-pulley 1^d connected with the roll 1^b. The apron 1 55 passes in and out through openings in the end walls of the drying-chamber. Apron 2 is supported in like manner upon rolls 2^a, 2^b, which are journaled in bearings outside the opposite ends of the drying-chamber, the roll 60 2^b being driven by means of a band 2^c passing around a band-pulley 2^d connected with such roll. Apron 2 also passes in and out of the drying-chamber through openings in the end-walls of the latter. 65

At 1^e is a feeding-apron at the receiving end of the apron 1, delivering onto the upper run of the said apron, and 2^e is a feeding-apron for the carrier-apron 2, feeding onto the upper run of the said apron 2. Feeding-apron 1^e is mounted upon supporting-rolls 1^f, 1^g, and feeding-apron 2^e is mounted upon supporting-rolls 2^f, 2^g. Upon roll 1^g is mounted a pulley 1^h, and upon roll 2^g is mounted a pulley 2^h, the said pulleys being 75 connected by means of a driving-band 1ⁱ passing around the same. Upon the roll 2^g is also mounted a pulley 2^k, while upon the roll 1^a is mounted a pulley 1^l. A driving-band 1^m connects the pulleys 1^h, 2^h, and 80 85 80 serves for transmission of rotary motion to the roll 2^g, whereby the feed-apron 2^e is actuated. By means of the band 1ⁱ the roll 1^g is actuated from the roll 2^g and thereby the feeding-apron 1^e is driven. 85

At 1°, Figs. 1, 2 and 3, is a delivery-apron for the carrier-apron 1, and at 2° is a delivery-apron for the carrier-apron 2. Apron 1° is supported upon the rolls 1^p and 1^q, and apron 2° is supported upon rolls 2^p and 2^q. Roll 1^q 90 is provided with a band-pulley 1^r, and roll 2^q is provided with a band-pulley 2^r, a band 1^s passing around the said pulleys 1^r, 2^r, so as to connect the rolls 1^q, 2^q, in a manner to cause them to turn in unison. The said rolls 95 1^q, 2^q, are actuated by means of a pulley 1^t which is connected with the roll 1^b and a band 1^u passing around the said pulley and a pulley 1^w which is connected with the roll 1^q.

The fan *F* draws the air from the interior 100 of the casing *A* below the lower run of the apron 2, through an opening *F'* in the adjacent side-wall of the casing *A*. The air thus drawn by the fan is forced by the latter upward through the coil-box, and the heated 105 air reenters the drying-chamber through

upper and lower openings L, m, in the former of which is located above the upper run of the carrier-apron 1, while the latter thereof is located at a height intermediate the upper and 5 lower runs of the said carrier-apron.

At H is a shaft extending across the drying-chamber above the upper run of the carrier-apron 1 and journaled in bearings in or upon the opposite side-walls of the casing A. To this 10 shaft are attached a series of fingers i, i, i.

J is a fixed arm on shaft H, and K is a weight carried by the said arm and adjustable thereon toward and from the axis of the shaft as shown in Fig. 8. K' is a clamping-screw by which the weight may be secured in adjusted position. The weight K acts with a tendency to turn the shaft H so as to hold the fingers i, i, i, pressed toward the upper run of the carrier-apron 1. These fingers 15 i, i, i, incline in the direction of movement of the said upper run, and they act to open up the stock as it is carried past them by the movement of the carrier-apron. In case the stock accumulates or masses up adjacent the 20 fingers i, i, i, it will press the said fingers up against the resistance of weight K, the said weight lifting and permitting the accumulation to travel onward. I have shown in Fig. 25 30 connection with carrier-apron 1. In practice, I may employ two series, or one, or more than two, in connection with one of each of the carrier-aprons. By sliding the weight K on the arm J the degree of the pressure of the fingers i, i, i, upon the stock upon the carrier apron may be varied. A fixed stop J' coacting with arm J prevents the fingers i, i, i, from resting on the carrier-apron.

For the purpose of withdrawing moisture-laden air from the interior of the machine and discharging it from the machine, when required, the outlet-duct or box B is furnished with a spout 80 leading therefrom. A slide-damper 79 is provided in connection 40 with the outlet-duct or box above the opening through which the said spout communicates with the interior of the outlet-duct or box. See more particularly Fig. 5. A fan 78 is provided in connection with the said 45 50 55 60 65 70 75 80 85 90 95 100 105 110 115 120 125 130 135 140 145 150 155 160 165 170 175 180 185 190 195 200 205 210 215 220 225 230 235 240 air from outlet-duct or box B when fan 78 is at rest, in the place of damper C.

What I claim is:

1. In a drier, in combination, the drying-chamber, a carrier-apron which carries the stock through the said chamber, and the swinging-fingers i, i, i, arranged to yield under pressure and operating to open up the said stock in its travel.

2. In a drier, the combination with the drying-chamber, and the carrier-apron which carries stock through the said chamber, of a series of swinging-fingers i, i, i, a shaft carrying the said fingers, and an adjustable pressure-device connected with the said shaft.

3. In a drier, the combination with the casing having a drying-chamber, and an outlet-duct or box for the escape of air from said chamber, of a fan in connection with said outlet-duct or box for withdrawing air from the machine and discharging the same from the machine, and a damper for closing the outlet-duct or box beyond its communication with the said fan during the operation of the latter.

4. In a drier, the combination with the casing having a drying chamber, and heating means, a fan for producing a circulation of air within the machine, an outlet-duct or box for the escape of air from said chamber, and a damper for regulating the rate of such escape, of a fan in communication with said outlet-duct or box for withdrawing air from the chamber and discharging the same from the machine, and a damper for closing the outlet-duct or box beyond its communication with the said fan during the operation of the latter.

5. In a drier, the combination with the casing having a drying chamber, air-heating means, a fan for producing a circulation of air within the machine, an outlet-duct or box for the escape of air from said chamber, and a damper for regulating the rate of such escape, of a fan in communication with said outlet-duct or box for withdrawing air from the chamber and discharging the same from the machine, and a damper for closing the outlet-duct or box beyond its communication with the said fan during the operation of the latter.

6. In a drier, the combination with the casing having a drying chamber, and heating means, a fan for producing a circulation of air within the machine, an outlet-duct or box for the escape of air from said chamber, and a damper for regulating the rate of such escape, of a fan in communication with said outlet-duct or box for withdrawing air from the chamber and discharging the same from the machine, and a damper for closing the outlet-duct or box beyond its communication with the said fan during the operation of the latter.
